(57) **CLAIM**

I claim, the ornamental design for an electric hydraulic pump body, as shown and described.

DESCRIPTION

FIG. 1 is a front right perspective view of an electric hydraulic pump body,

FIG. 2 is a rear right perspective view thereof,

FIG. 3 is a front left perspective view thereof,

FIG. 4 is a front view thereof,

FIG. 5 is a rear view thereof,

FIG. 6 is a top plan view thereof,

FIG. 7 is a bottom plan view thereof,

FIG. 8 is a left side view thereof; and,

FIG. 9 is a right side view of thereof.
